[57] **CLAIM**

[**] Term: **14 Years**

The ornamental design for a compressor for a vehicle air conditioner, as shown and described.

[21] Appl. No.: **29/099,608**

DESCRIPTION

[22] Filed: **Jan. 25, 1999**

FIG. 1 is a front elevational view of a compressor for a vehicle air conditioner showing our new design;

Related U.S. Application Data

FIG. 2 is a rear elevational view thereof;

[62] Division of application No. 29/062,161, Nov. 8, 1996, Pat. No. Des. 417,266.

FIG. 3 is a top plan view thereof;

Foreign Application Priority Data

FIG. 4 is a bottom plan view thereof;

May 9, 1996 [JP] Japan 8-013755
Jun. 6, 1996 [JP] Japan 8-016840

FIG. 5 is a left side elevational view thereof;

[51] LOC (7) Cl. **12-16**
[52] U.S. Cl. **D23/325; D23/354**
[58] Field of Search 418/259, 63; D23/325,
D23/354

FIG. 6 is a right side elevational view thereof;

References Cited

FIG. 7 is a perspective view thereof on a reduced scale showing a location for mounting the compressor of FIG. 1;

FIG. 8 is a front perspective view of the compressor of FIG. 1; and,

FIG. 9 is a rear perspective view thereof.

The broken-line showing of environmental structure in FIG. 7 is for illustrative purposes only and forms no part of the claimed design.
